UNITED STATES PATENT OFFICE.

ANTON J. HAEBLER, OF BALTIMORE, MARYLAND, ASSIGNOR, BY DIRECT AND MESNE ASSIGNMENTS, OF THIRTY-ONE SEVENTY-FIFTHS TO PETER H. THUMLERT, THOMAS MACKENZIE, AND HENRY C. GLOVER, OF SAME PLACE.

SPARK-ARRESTER.

SPECIFICATION forming part of Letters Patent No. 655,825, dated August 14, 1900.

Application filed March 26, 1900. Serial No. 10,270. (No model.)

To all whom it may concern:

Be it known that I, ANTON J. HAEBLER, of the city of Baltimore, in the State of Maryland, have invented certain Improvements in 5 Spark-Arresters, of which the following is a specification.

In the description of the said invention which follows reference is made to the accompanying drawings, forming a part hereof, 10 which illustrate the application of the invention to a locomotive-boiler, one of the many uses to which the invention is adapted.

Figure 1 is a sectional view of the smoke-box of a locomotive-boiler embodying the 15 present invention, the section being taken on the dotted line *x x*, Fig. 2. Fig. 2 is an exterior side view. Fig. 3 is a cross-section of Fig. 1, taken on the dotted line *y y*.

Referring now to the drawings, A is the 20 smoke-box of a locomotive-boiler, and B the smoke-stack, the upper end of which is outwardly flared, as shown in Fig. 1, for a purpose hereinafter described.

C is a casing or jacket placed around the 25 smoke-stack, whereby there is formed an annular space or pocket D to receive cinders thrown up by the exhaust-steam from the engine-cylinders. (Not shown.) This annular space is divided by the partition-plates *b* into 30 the semi-annular spaces *a*. Each of the semi-annular spaces *a* is in communication with a conduit E, situated exteriorly of the boiler and extending rearward in an inclined position. The two conduits unite at a point underneatn of the smoke-box and centrally 35 thereof and have a common outlet F for cinders.

Curved deflecting-plates G, attached to the 40 division or partition plates *b*, serve to guide the falling cinders to the cinder-conduits E.

H H are the exhaust-steam pipes leading from the engine-cylinders, (not shown,) terminating in a central vertical exhaust-pipe I.

J is a cylindrical screen constructed, preferably, in the main of wirework, extending from the central exhaust-pipe I, to which it is clamped, through the head *d* of the jacket C. This screen is by preference formed in three sections of different diameters, the larg-

est one being at the top and the smallest one 50 at the bottom or where it connects with the central exhaust-pipe I, and the mesh of the wirework is largest at the top and smallest at the bottom, as shown, for a purpose herein-after described. The screen allows of the free 55 passage of the exhaust-steam to the smoke-stack, and the portion of the steam which passes through the wall of the screen serves to carry the cinders from the smoke-stack to the semi-annular spaces *a* around the same, 60 in which they fall to the deflecting-plates G and are by them guided to the inclined cinder-conduits E, from which they escape by means of the outlet-opening F underneath 65 the boiler.

It will be understood that the screen J, notwithstanding that its wall is foraminous, is a continuation of the main exhaust-pipe I and differs only from it, in effect, in that there is a lateral, as well as a longitudinal, escape for 70 steam therefrom. It follows, therefore, that there is a tendency to a greater steam-pressure at the bottom of the screen or where it adjoins the main exhaust-pipe than at the top, where the steam escapes directly into the 75 atmosphere. I therefore facilitate the lateral escape of steam toward the top of the screen by increasing the size of the mesh of the wire-work from which the screen is made, and instead of the current of exhaust-steam passing 80 upward through the stack B in a succession of well-defined puffs there is a comparatively-even flow, which is better adapted to carry off the cinders from the smoke-box of the boiler.

The cinders are guided as they issue from the smoke-stack to the semi-annular spaces *a* by means of the flared sheet-metal portion *f* of the screen and the deflecting-plates K.

The operation of the invention is as follows: Cinders entering the smoke-box from the boiler-tubes (not shown) are carried upward by the force of the exhaust-steam escaping from the central exhaust-pipe and, striking the top deflecting-plates K, are turned 95 downward into the semi-annular spaces *a*, through which they fall by the force of gravity, aided somewhat by a slight steam-pres-

sure, to the deflecting-plates G, which guide them into the inclined cinder-conduits, from which they finally escape under the boiler.

I claim as my invention—

- 5 1. In combination with a smoke-box, a smoke-stack, and a steam-pipe leading to the said smoke-stack, a cinder-pocket, a cinder-conduit leading from the cinder-pocket, and a wirework screen which surrounds the end 10 of the steam-pipe, the mesh of the wirework increasing in size toward the top of the screen, substantially as specified.
- 15 2. In combination with the smoke-box of a locomotive-boiler, its smoke-stack, and the central exhaust-steam pipe leading from the engine-cylinders, a jacket placed around the said smoke-stack to form a cinder-pocket, a cinder-conduit leading from the cinder-pocket to a point underneath the boiler, and a wire- 20 work screen which extends from the central

exhaust-pipe through the head of the jacket, the mesh of the wirework increasing in size toward the top of the screen, substantially as specified.

3. In combination with the smoke-box of a locomotive-boiler, a smoke-stack and a steam-pipe leading to the said smoke-stack, a cinder-pocket, a cinder-conduit leading from the pocket, and a screen which surrounds the end of the steam-pipe, the portion of the said screen which is surrounded by the smoke-stack consisting of wirework in sections connected by a flared or conoidal deflecting-plate, substantially as, and for the purpose specified.

ANTON J. HAEBLER.
